UNITED STATES PATENT OFFICE

ALBERT DEMNITZ, OF DRESDEN, GERMANY

SOLE-LAYING DEVICE

Application filed July 29, 1925. Serial No. 46,863.

This invention relates to shoe sole laying devices and more particularly to pneumatic cushions for use in this connection.

According to the present practice in order to lay or stick soles to shoes it has been customary to press the shoe sole against the last by means of solid pressure members, such as rubber or cork plates, and the work piece held in place by means of spindles or the like.

10 This procedure is inconvenient and requires accurate fitting pressure members, the services of special workmen, and in addition to this consumes a relatively large amount of time.

15 This invention contemplates a pressure cushion which obviates the above drawbacks and has the special advantage that the pressure exerted during the operation of laying or sticking the sole to the shoe may be automatically generated and made regulable in order to improve the operation of the device.

A further object of the invention consists in providing a rubber bag having an air inlet and outlet on one side only of the bag and essentially at the central under part thereof. This arrangement provides for the free expansion in all directions of the rubber bag during its inflation within its container, which latter constitutes the leather outer cover, thereby avoiding not only distortions and defects of the rubber bag, but also causing the sole to be evenly and intimately laid against the upper part of the shoe.

In carrying out these objects the invention 35 is susceptible of modifications without departing from the spirit or sacrificing any of the advantages of the claimed invention.

In the accompanying drawings:

Figure 1 represents a longitudinal sectional view partly in elevation of the pressure device; and

Figure 2 is a top plan view with the pressure lever omitted.

In carrying this invention into effect the 45 pressure member proper is made somewhat

similar to a foot-ball and consists of an outer part made of leather or other flexible material shown at *a* and encases a pressure generating rubber bag *i* so that the irregular expansion of the rubber bag during its inflation will be limited by the stronger outer casting thereby protecting the bag against bursting.

The rubber bag *i* is equipped with a combined inlet and outlet valve *c* located at the central under part of the bag and by introducing pressure air into the bag *i* through the valve *c* a pressure will be first exerted against the sole of the shoe at the hollow under part or arch of the foot at the point designated *b* in Figure 1. This pressure will be distributed over the entire sole in such manner that the pressure surface of the bag will fit every part of the shoe to which the sole is fastened by the laying process.

This casing enclosed rubber bag *i* is placed upon a presser-form *g* between said form and the last *h* which latter is adapted and held in position by means of pressure bolts *d* and *e* pivoted to the pressure lever *k*. The pressure lever *k* is shown detachably connected by a link *l* with the form *g* at the rear thereof and the front of said lever is connected by a swiveled nut *m* with a threaded stud or rod *n* which projects upwardly from the front end 75 of the supporting structure of the device as is shown clearly in Fig. 1.

The casing *a* is formed in two parts as shown, stitched together at their marginal edges as indicated at *s*, the envelop thus formed being adapted effectively to resist pressures set up in the bag *i* when a shoe is forced against the cushion and to conform freely and accurately to the shape of the shoe bottom to which a sole is to be applied. Applicant's inflatable cushion does not require a special form of support or in other words the shape of the bottom wall of the presser form is immaterial, and does not have to be adjusted.

I claim:

In a machine for applying soles to shoes, an inflatable container comprising an interior rubber bag and a protecting covering therefor, said covering consisting of upper and lower pieces of leather completely surrounding and covering both sides of the bag, and stitching for uniting the meeting edges of the leather covering to completely enclose the bag and protect it from puncture, and permitting the upper surface of the leather to firmly engage the sole of the shoe.

In testimony whereof I have affixed my signature.

15
